GEORGE THOMAS OSBORN, OF ATLANTA, GEORGIA.

COLLAR.

1,250,635.

Specification of Letters Patent. Patented Dec. 18, 1917.

Application filed May 6, 1916. Serial No. 95,868.

To all whom it may concern:

Be it known that I, GEORGE T. OSBORN, a citizen of the United States, residing at Atlanta, in the county of Fulton and State of Georgia, have invented a new and useful 5 Collar, of which the following is a specification.

The present invention relates to an improvement in collars of the turn down type, 10 or to that type which is provided with an inner flap or fold adapted to fit against the neck and to be secured to the neck-band of the shirt.

An object of the present invention is to 15 provide a collar of this type with an inner fold of reduced diameter to admit the easy insertion, removal, and sliding of a necktie between the outer and inner folds of the collar; and to provide the inner fold with a 20 smooth and uninterrupted surface and eliminate all edges and sections which flare outwardly and bind against the necktie when the collar is secured in place.

Another object of the present invention is 25 to reduce the length of the inner fold of the collar, so that when the collar is curved or rounded into position, the inner fold is reduced in diameter, and is thus positively held in spaced relation and at a uniform 30 distance from end to end from the outer fold.

Prior attempts have been made to accomplish the result of permitting the free and 35 easy sliding of the necktie between the folds of the collar. These attempts embraced the slitting of the inner fold transversely, and the removal of portions of the material which are adapted to admit of the contraction of the inner fold when submitted to 40 pressure by pulling the tie. These structures do not reduce the diameter of the inner fold, and do not positively hold the inner fold in spaced relation from the outer fold. It is found that these prior structures present a 45 plurality of edges which catch the tie, and provide a plurality of tongues or separate portions which flare toward the outer fold and which serve to bind the tie tightly thereagainst. Furthermore, in providing these 50 recesses considerable material is wasted and considerable additional labor must be expended in the manufacture of the collar.

It is a further object of the present invention to provide means for reducing the 55 length of the inner fold which requires practically no waste of the material, and which

requires the exercise of but very little additional labor in the manufacture of the collar.

Other objects and advantages of this invention will be brought out in the following 60 detailed description of the present preferred embodiments thereof, the same being disclosed in the accompanying drawing, wherein—

Figure 1 is a perspective view of a collar 65 of the turn down type, showing the inner fold thereof constructed according to the present invention.

Fig. 2 is a longitudinal section taken on the line 2—2 of Fig. 1, showing the inner 70 and outer folds of a three-ply collar, spaced apart according to this invention, the plies, tucks and the resulting bulging being exaggerated.

Fig. 3 is a vertical section, taken on the 75 line 3—3 of Fig. 1, showing the inner fold flaring downwardly from the outer fold.

Fig. 4 is a fragmentary inner side elevation of the rear portion of a collar, showing the inner fold prior to its reduction. 80

Fig. 5 is a fragmentary perspective view of the rear portion of a collar, showing a modified construction of the inner fold.

Fig. 6 is a plan view of the collar spread out, and showing the lines of reduction of 85 the inner flap, according to the modification.

Fig. 7 is a longitudinal sectional view, taken on the line 7—7 of Fig. 5, showing the reduction at the opposite sides of the inner fold, and showing the latter spaced from 90 the outer fold.

Referring to this drawing, wherein like parts are designated by similar numerals of reference throughout the several views, 10 designates the outer fold of a turned down 95 collar, and 11 designates the inner fold of the same.

The present invention relates to the peculiar construction of the inner fold 11, which does not disturb the continuity of the fold or 100 interrupt the smooth inner and outer faces of the same. The present invention reduces the length of the inner fold 11, so that when it is curved into the usual form shown in Fig. 1, the inner fold 11 will be curved on a 105 diameter less than that of the outer fold 10 to positively hold the folds 10 and 11 in spaced apart relation, as shown in Fig. 2.

The present drawing shows the invention applied to a collar of the three-ply type, or 110 wherein the folds of the collar are made in three layers, or thicknesses of material. The

inner fold 11 is stitched in the usual manner to the upper edge of the outer fold 10. The inner fold 11 is reduced in length gradually from its upper to its lower edge, so that, as shown in Fig. 3, the inner fold 11 flares downwardly away from the outer fold 10.

To accomplish this result, the inner fold 11 by forming darts in the material is reduced along the downwardly diverging lines 12 and 13, which are shown to advantage in Fig. 4. In the preferred form shown in Figs. 1 to 4 inclusive, the portions of material 14 which are disposed between the lines 12, and the lines 13, are tucked or folded inwardly so as to lie between the plies or thicknesses of the fold.

The reduced portions of the inner fold 11 are disposed at the opposite sides of the fold, the innermost ply of the fold being reduced on the lines 12, while the two outer plies are reduced on the lines 13. The reduced portions are not only placed at the opposite sides of the fold 11, but are also spaced apart longitudinally of the folds, and thereby providing several darts so that the thicknesses of the fold or tucked in portions 14 will not come together. This will prevent any material raising of the inner and outer faces of the fold. When the lines or edges 12 and 13 are drawn together, they are stitched as at 15 to hold the inner fold 11 contracted or reduced, and to also hold the tucked or folded in portion 14 between the plies. As shown in Fig. 2, the stitches 15 are passed through the tucks 14 to hold the edges 12 and 13 together, and so that the stitches 15 lie between the plies and are not unduly exposed to view, forming substantially a French seam.

In Figs. 5, 6 and 7, there is shown a slightly modified form of the inner fold. In this modification, the inner fold 11 of the collar is reduced by forming a dart on lines 12^a and 13^a. These lines of reduction extend obliquely across the inner fold 11 and diverge downwardly from the upper edge thereof and at opposite sides of the buttonhole 16. The lines or edges 12^a are located on the inner ply of the fold, while the lines or edges 13^a are located upon the outer two plies of the fold. In this instance, the intervening portions 14^a of the material are removed by cutting the inner and the two outer plies along the lines 12^a and 13^a. The free diverging edges of the plies are now brought together, and secured by stitches 15^a, as shown in Fig. 7, to reduce the length of the inner fold 11, and hold it in spaced relation from the outer fold 10 when the collar is curved or rounded into shape.

Both forms of the invention provide an inner fold or flap for the collar which is continuous from end to end, and which has its inner and outer surfaces uninterrupted,

so that there is an annular space of equal size from end to end of the collar to freely receive the necktie and admit of the free slipping of the necktie between the folds of the collar. Whether the intervening portions 14 and 14^a are either tucked in or entirely removed from the plies of the flap, the flap has relatively smooth inner and outer faces, so that the collar presents substantially the same appearance as collars at present in use. It will be noted from the drawing that the reduced portions of the flap or fold are spaced equi-distantly from the opposite ends of the rear buttonhole 16 so that the inner fold is uniformly reduced at the opposite sides of the collar.

The portions 14 and 14^a are V-shaped so that when the fold 11 is drawn together it will be gradually reduced in length from its upper to its lower edge, and will flare away from the outer fold. In reducing the fold the plies may be grouped and tucked or cut in any desired manner, and the arrangement shown in the present drawing may be reversed.

It is, of course, understood that the invention is not limited to the number of plies or thicknesses of the collar.

What is claimed is:—

1. A collar having an outer fold and an inner fold formed of a plurality of plies, said inner fold which constitutes the band of the collar being reduced in length along lines diverging downwardly to the lower edge of the inner fold to space the lower part of the inner fold inwardly from the outer fold without destroying the continuity of said inner fold, the reductions being made in different plies and at points spaced apart longitudinally relatively to each other.

2. A collar having an outer fold, and an inner fold, said inner fold comprising a number of plies, some of said plies being reduced in length on downwardly diverging lines at one side of the fold, and the remaining plies being reduced in length on downwardly diverging lines at the opposite side of the fold and in longitudinally spaced apart relation to said first downwardly diverging lines whereby to reduce the length of the inner fold and space the same from the outer fold.

3. A collar having an outer fold, and an inner fold, the inner fold comprising a number of plies and having a rear buttonhole therethrough, the plies at one side of the inner fold being reduced in length along downwardly diverging lines spaced from one end of the buttonhole, and the plies at the opposite side of the fold being reduced in length along downwardly diverging lines spaced from the opposite end of the buttonhole so as to uniformly decrease the length of the inner fold from its upper edge to its lower edge and space the folds apart.

4. A collar having an outer fold, and an inner fold, formed of a plurality of plies, said inner fold being drawn together and stitched on downwardly diverging lines, the intervening portion between said stitched lines being tucked inwardly between the plies of the inner fold and secured therebetween.

5. A collar having an outer fold and an inner fold formed of a plurality of plies constituting the band of a collar and reduced in length along downwardly diverging lines extending from near the upper edge of the inner fold to near the lower edge thereof and stitched together to flare the fold inwardly and downwardly from the outer fold without destroying the continuity of the inner fold, the intervening portions

between said lines being provided in different plies and at points spaced apart longitudinally relatively to each other and tucked inwardly out of the way between the plies. 20

6. A collar having an inner fold, the intermediate portion thereof along downwardly diverging lines crosswise of said fold being drawn together and connected, whereby the inner fold at the lower portion is spaced inwardly from the outer fold. 25

In testimony that I claim the foregoing as my own, I have hereto affixed my signature 30 in the presence of two witnesses.

GEORGE THOMAS OSBORN.
